UNITED STATES PATENT OFFICE.

EDSON F. GALLAUDET, OF NORWICH, CONNECTICUT, ASSIGNOR TO GALLAUDET AIRCRAFT CORPORATION, OF NEW YORK, N. Y., A CORPORATION OF NEW YORK.

AEROPLANE.

1,262,660.

Specification of Letters Patent. Patented Apr. 16, 1918.

Application filed April 21, 1916. Serial No. 92,597.

To all whom it may concern:

Be it known that I, Edson F. GALLAUDET, a citizen of the United States, and a resident of the town of Norwich, in the county 5 of New London and State of Connecticut, have invented certain new and useful Improvements in Aeroplanes, of which the following is a specification.

My present invention relates to flying machines of the aeroplane type, and more particularly to the construction of the body portion of such machines and to the mounting of the propeller thereon.

The main object of the invention is to 15 provide a body for a flying machine, of stream line form adapted to house and protect the motor or motors and associated power mechanism, which shall be both strong and light in construction and upon 20 which the propeller is so mounted that it will be held rigidly in alignment with the power-shaft or shafts, that it will be protected largely from injury, and that it will assist in the cooling of the one or more 25 motors employed.

With this end in view the invention comprises certain novel features of construction, arrangement, and combination of parts hereinafter fully described and distinctly set 30 forth in the appended claims.

In the accompanying drawings, which form a part of this specification and wherein my improvements are shown, by way of illustration merely, as embodied in a bi- 35 plane machine,—

Figure 1 is a plan view, more or less diagrammatic, of the complete machine; Fig. 2, a section on the line 2 2 of Fig. 1, showing the body of the machine in side elevation; 40 Fig. 3, a detail, in longitudinal section on the line 3 3 of Fig. 4, showing the mounting of the propeller; and Fig. 4, a transverse section on the line 4 4 of Fig. 3.

Referring to the drawings, the machine 45 illustrated comprises, as its principal parts, the upper and lower supporting planes W W', the body B, mounted between the supporting planes and provided with suitable running gear, the propeller P, and the 50 usual rear elevating planes E E' and vertical steering rudder S.

The hollow body of the machine, preferably pisciform or torpedo-shaped as shown, is formed by a thin shell of suitable material, steel for example, which is made in or

divided transversely into two sections, a forward or main body section 1 and rear tail section 2, between which the propeller is mounted. The forward or main section of the body is provided with a suitable cockpit opening or openings 3 in its upper side forward, for the operator and his assistant, and within this section is mounted the power mechanism which comprises (as shown in dotted lines only) two gas engines M M' 60 and radiator R and fuel supply tank T, the radiator being set across the interior of the body in front of the engines. The sides of the tail section, which carries the steering rudder and elevating planes, are pierced 65 and upset to provide louver-like openings 4 therein, or, in place of these openings, the bottom of this section of the body may be left more or less open.

Within the rear end of the main body section, which is reinforced and stiffened internally by three flanged rings 5, 6, and 7, is mounted a drum 8. This drum, provided with outwardly projecting flange 9 at its forward and inwardly projecting flange 10 70 at its rear ends and an intermediate outwardly projecting flange 11, is held rigidly in place co-axial with the longitudinal axis of the body and extending somewhat beyond the end of the main body section by means 75 of two sets of radial arms 12 and 13 which are respectively bolted or otherwise secured at their outer ends to the flanged rings 5 and 6 and at their inner ends to the flanges 9 and 11 on the drum. A second drum 14, 80 of the same diameter as the first and provided with outwardly and inwardly projecting flanges 15 and 16 at its forward end and with outwardly projecting flange 17 at its rear end, is similarly mounted within 85 and substantially flush with the forward end of the tail section of the body by means of two sets of radial arms 18 and 19 which are respectively secured at their outer ends to two flanged rings 20 and 21 attached to 90 the walls of the body section and at their inner ends to the flanges 15 and 17 on the drum. This second drum is preferably closed at its rear end, to prevent the passage 95 of air, by a plate 22 which may be provided with suitable small openings (not shown) through which to pass the wires used for the control of the steering rudder and elevating planes.

The two sections of the body (after the 110

propeller and its ball-bearings, presently to be described, have been assembled and placed in position) are secured together by bolting the flanged front end of the drum 5 14 to the flanged rear end of the drum 8, leaving a narrow annular opening in the walls of the body between the adjacent ends of its main and tail sections within which the blades of the propeller revolve.

10 The propeller (still referring to Figs. 3 and 4) consists of a spool or hub 23, provided with gear teeth 24 cut around its forward end and two outwardly projecting flanges or annular plates 25, which is mounted 15 with suitable ball-bearings 26 to rotate upon the rear end of the drum 8, and blades 27 (shown as four in number, although the number is not material) which at their inner ends are bolted to the spool between 20 the annular plates 25 and project outwardly through the opening left in the walls of the body. Between or alternating with the propeller blades, and similarly secured to the spool, are one (as here shown) or more short 25 fan-blades 28, and bridge-pieces 29 in the form of segments of an annular plate, bearing against the outer ends of the intermediate fan-blade or blades, and secured by their flanged ends to the propeller blades to 30 bridge the opening left in the walls and so maintain the contour of the body.

Meshing with the teeth on the forward end of the propeller spool is a pinion 30 fixed to the rear end of a power-shaft 31 35 which is journaled in ball-bearings 32 and 33 suitably mounted the former in one of the lower radial arms 12 and the latter in a corresponding arm 13 which support the forward drum. The flanged front end of 40 this shaft is operatively connected in any suitable manner, preferably by a cone-clutch or other slightly flexible coupling, to the shaft of the engine M. A second pinion 30', also meshing with the teeth of the propeller spool, is fixed upon the end of a power-shaft, corresponding to the shaft 31, 45 which is similarly journaled in ball-bearings mounted in one of the lower radial arms 12 and 13 on the opposite side of the body and 50 coupled to the shaft of the engine M'.

The various parts described may be made of any suitable material, but, for the two drums, the propeller spool, and the driving pinions, I prefer to use the best chrome 55 nickel steel, heat treated. In practice, also, I prefer to stiffen the construction by longitudinally cross-bracing each of the two sets of radial arms which support the drums, although I have deemed it unnecessary to 60 show such cross-bracing.

It will be seen that by the construction above described I secure what is in effect a light armored body, substantially inclosed on all sides and of stream line form, which 65 houses and at the same time protects the en-

gines and practically all of the power mechanism. The propeller, with only its blades projecting outside the body, is not only protected from serious injury but also serves as an exhaust fan to cool the engines, drawing air in at the cock-pit openings and back through the radiator past the engines and through the annular channel between the drums and the walls of the body, and exhausting it through the louver openings in 70 the sides or through the open bottom of the tail section. Furthermore, a plurality of engines, one or all of which may be used as desired, are directly connected by spur gears to the single propeller, thus securing a maximum of efficiency and elasticity of power, while the power shafts and driving pinions are rigidly held in fixed alinement with the propeller spool no matter what the stresses to which the body of the machine may be 75 subjected. Still other advantages will be apparent to a manufacturer or practised operator.

While I have explained the principle of my invention and have illustrated and described what I now consider to be the best form in which to embody that principle, it will be understood that the invention may be variously modified in its several parts, within the scope of the appended claims, 85 without departing from the spirit or sacrificing the advantages thereof.

What I claim as new, and desire to secure by Letters Patent, is—

1. In a flying machine, an elongated body 100 which is substantially inclosed on all sides, a gas engine mounted within the body, a radiator for the engine set entirely across the interior of the body forward of the engine, and a propeller which is mounted within the body to the rear of and in operative connection with the engine and with blades projecting outwardly through a transverse opening in the walls of the body and is adapted to draw air through the radiator 105 and assist in the cooling of the engine.

2. In a flying machine, an elongated rearwardly tapering body the walls of which are formed by a steel shell substantially inclosing it on all sides and power mechanism 110 including a propeller and a gas engine and a radiator therefor mounted within the body, the radiator being set entirely across the body in front of the engine and the propeller being mounted to the rear of the engine co-axial with the longitudinal axis of the body with blades projecting outwardly through a transverse opening provided therefor in the walls and adapted to serve as a fan to assist in the cooling of the engine.

3. In a flying machine, a hollow pisciform body, a plurality of gas engines mounted side by side within the body, a radiator for the engines set across the interior of the 115 120 125 130

body forward of the engines, a propeller mounted within the body to the rear of the engines with blades projecting outwardly through a transverse opening in the walls of 5 the body and adapted to draw air through the radiator and past the engines, and means for operatively connecting one or all of the engines with the propeller.

4. In a flying machine, an elongated and 10 substantially inclosed hollow body, a propeller mounted within the body coaxial with its longitudinal axis and with blades projecting outwardly through a transverse opening provided therefor in its walls, a plurality of engines mounted within the body, and means located within the body 15 for operatively connecting each or all of the engines with the propeller.

5. In a flying machine, an armored body 20 substantially of stream line form, a propeller mounted within the body coaxial with its longitudinal axis and with blades projecting outwardly through a transverse opening in its walls, a plurality of driving 25 shafts geared to the hub of the propeller and mounted to rotate in bearings rigidly secured in position relative to the bearings of the propeller, a plurality of engines mounted within the body, and means for 30 coupling each engine with one of the driving shafts.

6. In a flying machine, an elongated hollow body of substantially stream line form divided transversely into front and rear sections, a hollow cylindrical drum rigidly mounted within the adjacent ends of the two body sections coaxial therewith and serving to unite them together, and a propeller mounted to rotate upon the drum with 35 blades projecting outwardly between the adjacent ends of the body sections.

7. In a flying machine, an elongated hollow body of substantially stream line form divided transversely into front and rear sections, a hollow cylindrical drum rigidly mounted within the rear end of the front body section, a propeller mounted to rotate upon the drum immediately behind the rear end of the front body section, a driving 45 shaft geared to the hub of the propeller and mounted to rotate in bearings rigidly secured between the drum and the walls of the body section, and means for securing the rear body section to the drum immediately 50 behind the propeller.

8. In a flying machine, an elongated rearwardly tapering body with walls formed by a shell which is divided transversely to form a forward main body section substantially 60 symmetrical in transverse section and a rear tail section, a drum which is rigidly mounted co-axially within and extends slightly beyond the rear end of the main body section and to the rear end of which the tail 65 section of the body is secured so as to leave

a narrow transverse opening between the forward edge of its walls and the rear edge of the walls of the main body section, a propeller which is mounted to rotate upon the rear extended end of the drum with 70 blades projecting outwardly through the opening between the adjacent edges of the walls of the main and tail body sections, and means for operatively connecting the propeller to a source of power located within 75 the forward main body section.

9. In a flying machine, an elongated rearwardly tapering body with walls formed by a shell which is divided transversely to provide a forward main body section and a 80 rear tail section, a drum which is rigidly mounted by means of radial arms co-axially within and extends slightly beyond the rear end of the main body section and to the rear end of which the tail section of the 85 body is secured, a propeller which is mounted to rotate upon the rear extended end of the drum with blades projecting outwardly through an opening left between the adjacent edges of the walls of the main and tail body sections, and a power-shaft geared to the propeller which is journaled in bearings mounted in the radial arms which secure the drum and is adapted to be operatively connected to the shaft of an engine located 90 within the forward main section of the body.

10. In a flying machine, a hollow pisciform body which is divided into front and rear sections, a drum which unites the two body sections and provides a bearing for a 100 propeller coaxial with the longitudinal axis of the body, and a propeller mounted to rotate upon the drum which has propeller blades extending outwardly between the two body sections beyond their walls and, intermediate said blades, bridging pieces adapted to maintain the contour of the body and fan blades extending outwardly to the bridging pieces.

11. In a flying machine, an elongated 110 rearwardly tapering body which comprises an inclosed forward main body section adapted to receive and house the power mechanism and a rear tail section which is secured to the forward section near the longitudinal axis of the body so as to leave a narrow transverse opening in the walls between the adjacent ends of the two sections, a propeller which is mounted co-axially within the body opposite and with propeller blades projecting outwardly through the said opening in its walls and is provided intermediate the propeller blades with fan blades and with bridge-pieces adapted to bridge the opening therein and maintain the 115 contour of the body, and a power-shaft geared to the propeller which is journaled in bearings holding it rigidly in position parallel to the axis of the propeller and is adapted to be operatively connected by a 120 125 130

flexible coupling to the shaft of an engine located in the forward main section of the body.

12. In a flying machine, an elongated rear-
wardly tapering body which is substantially
inclosed and armored by a steel shell di-
vided transversely into a forward main body
section adapted to receive and house the
power mechanism and a rear tail section, a
steel drum which is rigidly mounted by
means of radial arms co-axially within and
extending slightly beyond the rear end of
the main body section and to the rear end
of which the tail section of the body is se-
cured, a propeller which is mounted to ro-
tate upon the rear extended end of the drum
with its blades projecting outwardly
through an opening left between the adjac-
ent edges of the walls of the main and tail
body sections and which intermediate its
blades is provided with fan blades and with
bridge-pieces adapted to bridge the said open-
ing left in the walls and maintain the con-
tour of the body, and a power-shaft which
is geared to the propeller and journaled in
bearings holding it rigidly in position par-
allel to the axis of the propeller and is
adapted to be operatively connected to the
shaft of an engine located in the forward
main section of the body.

13. In a flying machine, a hollow body
of substantially stream line form divided
transversely into two sections, a hollow cy-
lindrical drum of smaller diameter rigidly
mounted within the inner end of one body
section coaxial therewith and projecting
therefrom, means uniting the other body
section to the projecting end of the drum,

a propeller mounted to rotate upon the drum
between the two body sections, a driving 40
shaft geared to the propeller and journaled
in bearings located within the first men-
tioned body section and rigidly secured in
position relative to the drum, an engine
mounted within the first mentioned body 45
section, and means for flexibly coupling the
engine with the driving shaft.

14. In a flying machine, a hollow body
of substantially stream line form divided
transversely into two sections, a hollow cy-
lindrical drum of smaller diameter rigidly
mounted within the inner end of one body
section coaxial therewith and projecting
therefrom, means for uniting the other body
section to the projecting end of the drum, 50
two driving shafts geared to the propeller
and journaled in bearings located within the
first mentioned body section and rigidly se-
cured in position relative to the drum, two
engines mounted within the first mentioned 55
body section, and means for flexibly cou-
pling each engine with one of the driving
shafts.

15. In a flying machine, an elongated hol-
low body divided transversely into two sec-
tions, a hollow cylindrical drum of smaller
diameter rigidly mounted within the adja-
cent inner ends of the two body sections co-
axial therewith and serving to unite them
together, a radiator set across the interior 65
of the body and an engine mounted within
one of the body sections, and a propeller
mounted to rotate upon the drum between
the two body sections and operatively con-
nected with the engine.

EDSON F. GALLAUDET.
